GIRDLE SUPPORTING MEANS

Nell Moline Pfann, New York, N. Y., assignor to
 I. B. Kleinert Rubber Company, New York,
 N. Y., a corporation of New York

Application September 21, 1939, Serial No. 295,866

2 Claims. (Cl. 24—248)

This invention relates to girdles and similar garments for women and more particularly to such undergarments provided with supporting means therefor.

It is well known that girdles, particularly those composed of two-way stretch material possess the objectionable characteristic of rolling down at the waistline of the wearer. Numerous attempts have been made to obviate this disadvantage but they have not been entirely successful and have in some cases resulted in the introduction of other objectionable characteristics in the girdle. For example, stiffening elements utilized for preventing rolling of the girdle are frequently objectionable because they stiffen in the waist portion of the girdle, interfere with the elasticity thereof, and are for these and other reasons uncomfortable. Furthermore, the use of stiffening elements adds bulk to the waist portion of the girdle while on the other hand, particularly in view of present style trends the wearer's waist should be as slender as possible and on that account the use in connection with the girdle of stiffening means is further undesirable.

In accordance with the present invention provision is made for preventing the girdle from rolling and this is accomplished without stiffening the waist portion of the girdle or reducing the elasticity thereof and without substantially adding to the bulk of the waist portion of the girdle. For this purpose provision is made for supporting the waist portion of the girdle to prevent rolling thereof and to support the girdle in position by means suspended from the shoulders of the wearer and attached to the upper marginal edge portion of the girdle.

The invention will be more fully understood from the following description considered with reference to the accompanying illustrated drawings:

In the drawing:

Fig. 1 is a view of the girdle and support therefor embodying the present invention, shown in position on the wearer;

Fig. 2 is a front view in elevation of the lower end of one of the straps detached from the girdle;

Fig. 3 is an edge view in elevation of the part of the strap shown in Fig. 2;

Fig. 4 is a perspective view of the end of a strap, the clasp being shown in open position;

Fig. 5 is a view of the lower back portion of the supporting means, shown detached from the girdle;

Fig. 6 is an edge view of the part shown in Fig. 5;

Referring now to the drawing in detail, the girdle 10 illustrated in Fig. 1 of the drawing may be of any suitable construction and is customarily formed of two-way stretch fabric and also as usual, is circumferentially continuous and elastic being ordinarily formed from a tubular blank of two-way stretch fabric. Said girdle may be a panty girdle, i. e., with a crotch piece, or an ordinary girdle. It will be understood that the upper edge of the girdle, when worn, is positioned at the waist of the wearer.

The means provided in accordance with the present invention for supporting the girdle and for preventing rolling thereof, comprises straps 12 adapted to be suspended from the shoulder of the wearer and connected to the top marginal edge portion of the girdle by releasable clasps 14 at the front and back of the girdle. Said straps are relatively narrow and have sections 16 composed of fabric tape which is preferably inextensible. The front portions of straps 12 are provided with buckles 18 and 20 for adjustment of the length of the strap. Similar buckles are provided at the rear portions of the strap as illustrated in Figs. 5 and 6. The rear portions of the strap are connected together in V formation by a strip of fabric tape 22, also preferably inextensible, passed through a buckle 24 and secured at its opposite ends to buckles 20 at the back of the wearer. The front ends of straps 16 are connected to longitudinally elastic strap members 26 associated with the clasp 14, and similarly at the back of the supporting means, the strap portion 22 is connected by means of a buckle 24 to a longitudinally elastic strap member 26 associated with the clasp 14.

Clasp 14 comprises a jaw 28 having at one end thereof a slotted portion 30 in which a looped end 32 of strap member 26 is secured. The other looped end 34 of strap 26 is secured to the metal loop 36 which is pivoted at its ends in the side ears 38 of the clasp member 40. The other jaw 42 of the clasp is pivotally mounted on a U-shaped link 44 which is pivoted at the outer ends of the legs thereof to the ears 38 of clasp member 40. Jaw 28 is pivotally connected to member 40 by a pivot pin 46 secured at its ends between ears 38. Clasp member 40 provides means for opening and closing jaws 28 and 42 and also overlies and covers said jaws at the front of the clasp. It will be observed that a part of strap member 26 extends over the back of the clasp thereby covering the latter and preventing contact of the metal parts of the clasp with the wearer's body.

When the supporting device is attached to the

girdle, the upper edge portions of the girdle at the front thereof is engaged by a pair of clasps 14, the material of the girdle being engaged between and clasped by the opposed jaws 28 and 42, while at the back of the girdle the clasp 14 similarly engages the upper edge portion of the girdle centrally in the back thereof. The length of straps 12 can be adjusted as desired by the above described adjustable portions. It is thus seen that the girdle is properly supported in position on the wearer and that rolling of the waist portion is effectively prevented. Thus it is seen that the girdle provided with the supporting means of the present invention is free from the objectionable features of the prior art constructions particularly the stiffening device heretofore utilized for preventing rolling of the girdle. It will be understood that the clasps 14 are thin and flat and therefore do not add to the bulk at the waist portion of the girdle. In this connection, it will be further understood that the upper waist portion of the girdle can be of a single thickness of material, it being unnecessary to fold the upper part of the girdle or to add to the thickness thereof by strips of fabric sometimes used for securing the stiffening stays or similar roll-preventing means of the prior art device.

Thus it is seen that the girdle and the supporting means therefor, herein shown and described are well adapted to accomplish the several objects of the present invention. It will be understood, however, that while I have shown and described the preferred embodiment of the invention the latter may be embodied otherwise than as here shown and that in the form of the invention herein disclosed certain changes in the details of construction and in the arrangement of parts may be made. Therefore, I do not wish to be limited to the form of the invention herein shown or described, except as may be required by the scope of the appended claims.

Having thus described my invention, what I claim and desire to secure by Letters Patent are:

1. Supporting means comprising a strap having an elastic end portion and a clasp attached to said elastic end portion, said clasp comprising a first jaw member, a second jaw member pivotally connected to said first jaw member, a cover and jaw-operating member pivotally connected to said two jaw members at one end of the clasp 10 and operative to open and close said jaw members, said first jaw member having a slot at the opposite end of the clasp, a part of said elastic strap covering the back of the clasp and connected at one end thereof to said clasp in said 15 slot, and a part of said elastic strap being connected at the other end thereof to said cover member at the first mentioned end of the clasp, said end portion of the strap being folded between its ends, and a buckle through which said 20 end portion extends and which engages the latter at the folded part thereof.

2. Supporting means comprising a strap having an elastic end portion and a clasp attached to said elastic end portion, said clasp comprising 25 a first jaw member, a second jaw member pivotally connected to said first jaw member, a cover and jaw-operating member pivotally connected to said two jaw members at one end of the clasp and operative to open and close said jaw members, said first jaw member having a slot at the opposite end of the clasp, a part of said elastic strap covering the back of the clasp and connected at one end thereof to said clasp in said 30 slot, a loop member connected to said cover member at the first mentioned end of the clasp, said elastic strap being connected at the other end thereof to said loop member, said end portion of the strap being folded between its ends, and a buckle through which said 35 end portion extends and which engages the latter at the folded part thereof.
